UNITED STATES PATENT OFFICE.

GEORGE R. OSBORN, OF NEW YORK, N. Y.

DESIGN FOR AN EASEL.

SPECIFICATION forming part of Design No. 16,617, dated April 13, 1886.

Application filed March 1, 1886. Serial No. 193,684. Term of patent 14 years.

To all whom it may concern:

Be it known that I, GEORGE R. OSBORN, a citizen of the United States, residing at New York, in the county of New York and State of New York, have invented and produced a new and original Design for Easels; and I do declare the following to be a full, clear, and exact description of the same, reference being had to the accompanying drawing, forming a part thereof.

The leading feature of my design consists of a conventional imitation of a rustic-work frame, so designed that the cross-bars of the easel appear to lie across crotches where twigs have been cut from the upright stems of the easel.

The annexed drawing represents a perspective view of my newly-designed easel.

Each upright A represents a conventional imitation of a stick with the bark on and with stub ends a and a' of cut off twigs. A lower cross-bar, B, lies across the crotches formed by the stub ends a, while an upper cross-bar, C, lies across the crotches formed by the stub ends a'. Both cross-bars project at each end beyond the crotches, and represent conventional imitations of sticks with the bark on. The ends of the cross-bars and stub ends, as well as the upper ends of the uprights, are

slanting, to convey the effect of slantingly-cut sticks. The upper portion of each upright A has a graceful outward curve. From each stub end a a chain, D, extends to the brace E of the easel. The slanting ends add greatly to the beauty and naturalness of my design; but they are not absolutely essential features thereof.

I claim as my invention—

1. The design for an easel herein shown and described, the same consisting of a conventional imitation of a rustic frame having an upper and a lower cross-bar intermediate the upper and lower ends of the uprights, which cross-bars respectively cross crotches on the said uprights.

2. The design for an easel herein shown and described, the same consisting of a conventional imitation of a rustic-work frame, in which the cross-bars respectively cross crotches on the uprights, and in which the upper portion of each upright is curved outwardly.

In testimony whereof I affix my signature in presence of two witnesses.

GEORGE R. OSBORN.
